UNITED STATES PATENT OFFICE.

RUDOLPH C. HARTLEB AND THOMAS J. LEVEY, OF BALTIMORE, MARYLAND, AS-SIGNORS TO THE CAMBRIDGE MECHANICAL TOY COMPANY, OF CAMBRIDGE, MARYLAND, A CORPORATION OF MARYLAND.

FIGURE WHEELED TOY.

1,391,829.

Specification of Letters Patent. Patented Sept. 27, 1921.

Application filed September 28, 1920. Serial No. 413,379.

To all whom it may concern:

Be it known that we, RUDOLPH C. HARTLEB and THOMAS J. LEVEY, both citizens of the United States, each residing at Baltimore, in the county of Baltimore and State of Maryland, have invented certain new and useful Improvements in Figure Wheeled Toys; and we do hereby declare the following to be a full, clear, and exact description 10 of the invention, such as will enable others skilled in the art to which it appertains to make and use the same.

This invention relates to toys and has for its object to provide a doll seated in a carriage and having its head, arms, and legs so connected to the axles of the wheels of the carriage that upon moving the carriage the said head, arms, and legs will likewise move. A further object of the invention is 20 to construct a doll having the above characteristics in a manner comparatively less costly and which will be more pleasing in action than those which have been heretofore proposed.

With these and other objects in view the invention consists in the novel details of construction and combinations of parts more fully hereinafter disclosed and particularly pointed out in the claims.

Referring to the accompanying drawings forming a part of this specification in which like numerals designate like parts in all the views;

Figure 1 is a side elevational view of a 35 doll and a carriage made in accordance with this invention;

Fig. 2 is a longitudinal sectional view in elevation of the parts shown in Fig. 1;

Fig. 3 is a longitudinal sectional view in 40 plan of the parts shown in Fig. 1; and

Fig. 4 is a transverse sectional view of the parts shown in Fig. 1 illustrating with greater particularity the connections by which the arms and legs are moved.

45 1 indicates any suitable carriage or support for the doll; 2 the front wheels thereof; 3 the rear wheels; and 4 any suitable means for propelling the carriage 1. The axle 5 of the front wheels 2 is provided with the 50 crank 6 to which is connected the pitman or link 7 which is pivoted as at 8 to the crank 9, secured to the vertical rod 10, connected as at 11 to the vertically disposed member 12 rigid with the head 13 of the doll. The

said member 12 is conveniently housed in a 55 casing 45 so that it is held in place while the head 13 oscillates from side to side. Also connected to the crank 6 is the link 15 attached as at 16 to the bellows or noise making device 17 provided with an opening 18 60 and a flap or reed 19 which is adapted to admit air through the opening 18 and to emit a sound when the member 17 is moved up and down through the member 15. 20 represents the supports for the forward 65 wheels 2 and 21 represents the supports for the rear wheels 3. These said supports are conveniently made of wooden members fitted into the bottom 23 of the carriage 1 as shown, and provided at their lower ends with the 70 staples 25 through which the rear axle 26 passes. Said rear axle 26 is bent to form the crank 27, to which is pivoted the link 28, which in turn is pivoted as at 29 to the connecting rod 30, which latter is joined as 75 at 31 to the right hand leg 32 of the figure and is also joined as at 33 to the right arm 34 of the figure. The rear axle 26 is also bent to form the crank 35, to which is pivoted the link 36 joined at 39 to the left hand 80 leg 40 of the figure and is also joined at 41 to the left arm 42 of the figure. 43 represents clothes or other covering for the figure. 45 represents a wooden standard which supports the members of the doll and to said 85 standard is pivoted as at 46 the legs 32 and 40 and above said legs is pivoted the arms 34 33 and 42, all as will be clear from the drawings.

In operation the child pushes as by the 90 handles 4 the carriage 1, which causes the front wheels 2 and the rear wheels 3 to revolve. The turning of the front wheels 2 turns the crank 6 which reciprocates the pitman 7 which oscillates the crank 9, which 95 oscillates the rod 10 and the member 12, which in turn oscillates the head 13. The turning of said crank 6 also reciprocates the member 15 which moves up and down the member 17 and causes the bellows to 100 produce a squeak or other noise. The rotation of the rear wheels 3 turn the cranks 27 and 35, which reciprocate the members 28 and 36 respectively. The reciprocation of the member 28 reciprocates the connection 105 30 which lifts and lowers the right leg and right arm of the figure. The reciprocation of the member 36 causes the reciprocation of

the member 38, which raises and lowers the left leg and arm of the figure. The said cranks 27 and 35 being angularly displaced by say 180° , as the right arm and leg go up, 5 the left arm and leg go down.

It thus results that as the carriage is moved the figure's head turns from right to left and its arms and legs alternately move upward and downward, while the bellows 17 10 produces a noise.

It is obvious that those skilled in the art may vary the details of construction as well as the arrangement of parts without departing from the spirit of the invention, and 15 therefore we do not wish to be limited to the above disclosure except as may be required by the claims.

What we claim is:—

1. In a toy the combination of a support; 20 front wheels and rear wheels provided with axles turning therewith for carrying said support; a figure mounted on said support having arms and legs, and a head adapted to oscillate from side to side; a vertically disposed member rigid with said head and provided with a crank; a second crank, carried by the axle of said front wheels; a connection between said cranks for oscillating said head as said front axle revolves; 25 a third crank, carried by the rear axle; and a connection between said third crank and a leg and an arm for moving the latter up and down as said third crank revolves; substantially as described.

2. In a toy the combination of a support; 35 front wheels and rear wheels provided with axles turning therewith for carrying said support; a figure mounted on said support having arms and legs, and a head adapted 40 to oscillate from side to side; a vertically disposed member rigid with said head and provided with a crank; a second crank, car-

ried by the axle of said front wheels; a connection between said cranks for oscillating said head as said front axle revolves; a 45 third crank, carried by the rear axle; a connection between said third crank and one of said legs and arms for moving the latter up and down as said third crank revolves; a fourth crank, also carried by said rear 50 axle; and connections between said fourth crank and the other leg and arm for operating the latter as said rear axle revolves, substantially as described.

3. In a toy the combination of a support; 55 front wheels and rear wheels provided with axles turning therewith for carrying said support; a figure mounted on said support provided with pivotally connected arms and legs, and having a head adapted 60 to oscillate from side to side; a vertically disposed member rigid with said head and provided with a crank; a second crank, carried by the axle of said front wheels; a connection between said cranks for oscillating 65 said head as said front axle revolves; a bellows for making a squeak; a connection between said bellows and said second crank for operating said bellows; a third crank carried by the rear axle; a connection between said third crank and a leg and an arm for moving the latter up and down as said third crank revolves; a fourth crank, carried by said rear axle in angularly disposed relation to said third crank; and a connection between said fourth crank and the other arm and leg, for moving the latter 70 up and down as said crank revolves, substantially as described.

In testimony whereof we affix our signatures.

RUDOLPH C. HARTLEB.
THOS. J. LEVEY.
